US00D952289S

(12) **United States Design Patent** (10) **Patent No.:** **US D952,289 S**
(45) **Date of Patent:** **** May 24, 2022**

(54) **BRASSIERE**

(71) Applicant: **Under Armour, Inc.**, Baltimore, MD (US)

(72) Inventors: **Ofra Inselberg**, Baltimore, MD (US);
Maxi Roberts, Baltimore, MD (US);
Jessica LaCava, Baltimore, MD (US);
Abby Wittstadt, Baltimore, MD (US)

(73) Assignee: **UNDER ARMOUR, INC.**, Baltimore, MD (US)

(***) Term: **15 Years**

(21) Appl. No.: **29/723,502**

(22) Filed: **Feb. 7, 2020**

(51) LOC (13) Cl. **02-01**

(52) U.S. Cl.

USPC **D2/706; D2/708**

(58) **Field of Classification Search**

USPC D2/702, 703, 706-710, 718-727, 731,
D2/737, 739

See application file for complete search history.

(57) **CLAIM**

The ornamental design for a brassiere, as shown and described.

DESCRIPTION

FIG. 1 is a first rear perspective view of a brassiere showing my new design;

FIG. 2 is a second rear perspective view of the brassiere of FIG. 1;

FIG. 3 is a front perspective view of the brassiere of FIG. 1; FIG. 4 is a rear view of the brassiere of FIG. 1;

FIG. 5 is a front view of the brassiere of FIG. 1;

FIG. 6 is a right side view of the brassiere of FIG. 1;

FIG. 7 is a left side view of the brassiere of FIG. 1;

FIG. 8 is a top view of the brassiere of FIG. 1; and,

FIG. 9 is a bottom view of the brassiere of FIG. 1.

The broken lines in the figures are for environmental purposes only and form no part of the claimed design.

1 Claim, 9 Drawing Sheets
